UNITED STATES PATENT OFFICE

130,267

DESIGN FOR A LAPEL WATCH

David Taylor, New York, N. Y.

Application August 22, 1941, Serial No. 102,987

Term of patent 3½ years

To all whom it may concern:

Be it known that I, David Taylor, a citizen of the United States of America and a resident of the county of Bronx, city and State of New York, have invented a new, original, and ornamental Design for a Lapel Watch, of which the following is a specification, reference being had to the accompanying drawing, forming a part thereof.

On the drawing:

Figure 1 is a front view in elevation of a lapel watch showing my new design.

Figure 2 is a side view in elevation, the side not shown being similar to the side shown except for the absence of winder.

I claim:

The ornamental design for a lapel watch, as shown and described.

DAVID TAYLOR.
